UNITED STATES PATENT OFFICE.

EMIL A. SCHUELKE, OF NEW YORK, N. Y.

DESIGN FOR A BRACELET.

Application filed June 1, 1925. Serial No. 13,619. Term of patent 3½ years.

To all whom it may concern:

Be it known that I, EMIL A. SCHUELKE, a citizen of the United States, residing at New York, in the county of New York and State of New York, have invented a new, original, and ornamental Design for Bracelet, of which the following is a specification, reference being had to the accompanying drawing, forming a part thereof, in which—

I claim:

The ornamental design for a bracelet, as shown.

EMIL A. SCHUELKE.
